UNITED STATES PATENT OFFICE

ROSS A. WORKMAN, OF TULSA, OKLAHOMA

SHEET METAL ROOF

Application filed November 1, 1929. Serial No. 404,156.

The present invention relates to sheet metal roofs, and aims to provide a roof composed of sheet metal elements having novel means to engage one another for attaching the elements together and preventing leakage between them.

The improvements may be embodied in imitation tile or shingles composed of sheet metal, or may be embodied in roofing sections composed of corrugated sheet metal, and have other similar uses.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

20 The invention is illustrated in the accompanying drawing, wherein—

Figure 1 is a fragmentary plan view of the sheet metal roof embodying imitation tile composed of sheet metal, portions being broken away and shown in section.

Figs. 2 and 3 are sectional views on the respective lines 2—2 and 3—3 of Fig. 1.

Fig. 4 is a perspective view of one of the imitation tiles.

30 Fig. 5 is a butt end view of imitation shingles of sheet metal embodying the improvements, portions being broken away and shown in section.

Fig. 6 is a sectional view illustrating the 35 improvements embodied in corrugated sheet metal roofing.

As shown in Figs. 1, 2, 3 and 4 the invention is embodied in a sheet metal roof composed of imitation tiles made from sheet 40 metal. Each "tile" or roof element is constructed from sheet metal, and has the longitudinal arched portion 1 giving the tile appearance. The roof element has the flat broad portion 2 at one side whose free edge 45 is bent upwardly to form a hook 3, and the roof element has the narrower flat portion 4 at the opposite side of the arched portion 1.

From the portion 4 an upwardly curved portion 5 extends behind or below the corresponding side of the arched portion 1,

with a doubled portion 6 between the portion 5 and corresponding edge of the portion 1.

The doubled portion 6 is resilient or flexible to provide for yielding action, and is spaced above the portion 4 to provide a slot 7 to receive the hook 3 of the companion roof element, said elements being arranged side by side in courses as tiles are usually laid.

The hook 3 of one roof element is readily introduced through the slot 7 of the companion roof element, with said elements at an obtuse angle to one another, and when said elements are swung into substantially the same plane, the hook or portion 3 rides along the portion 5 and comes into abutment with the portion 6 at the juncture of the portions 5 and 6, thereby providing a tight fit, and the portion 6 may yield if necessary.

The portion 6 is spaced from the portion 5 and is so arranged that it is spaced from the portions 2 and 3 excepting along the edge of the portion 3 where it abuts the portion 6 immediately adjacent to the juncture between the portions 5 and 6. Water may thus flow along the portions 2 and 3 without being raised by capillary action between the portions 3 and 6.

The portion 4 over which the portion 2 of a companion roof element or tile extends, has an upstanding longitudinal rib 8 on which the portion 2 seats, to provide a tight line of contact between said portions 2 and 4.

45 The contact of the portion or hook 3 with the portion 6 will prevent moisture from escaping downwardly between the roof elements, and the contact of the portion 2 with the rib 8 will provide additional assurance against leakage. Moreover, any moisture flowing down the portion 5 will run along the rib 8 to be discharged from the lower end of the element or tile.

The portion 4 has one or more nail holes 9 through which one or more nails 10 or other securing elements are driven into the boards underneath.

50 The arched portion 1 has a downturned or inturned flange 11 at its lower end, and the portions 2 and 4 also preferably have downturned flanges 12 and 13 integral with

100

the flange 11, to give the roof element the appearance of the lower thick end of a tile. The portion 4 may also have a longitudinal flange 14 along its edge to stiffen said portion.

The roof elements or tiles of each course are overlapped, and the elements of the successive courses are also overlapped similar to roof tiles as usually laid, the lower ends 10 of each course of roof elements overlapping the upper end portions of the next course below.

The flange 11 of each roof element preferably has a downwardly extending lip 15 to fit snugly over the arched portion 1 of the next lower element.

Fig. 5 illustrates the improvements embodied in sheet metal shingles having the top portions 1a with the downwardly offset 20 portions 2a and 4a. The portions 2a and the hooks or curved portions 3a fit the curved portions 5a and abut the doubled portions 6a, similar to the construction above described, there being a slot 7a between the portions 4a and 6a. The rib 8a, as shown, is so arranged as to be engaged by the bend between the portion 2a and the body of the shingle, to provide a wedging contact.

25 The top portions 1a have the depending flanges 11a at their lower ends to constitute the butt ends of the shingles. The shingles are laid similar to the tile or roof elements above described, the portion 3a being inserted through the slots 7a and the shingles swung downwardly into place in succession. The portions 4a are secured on the boards underneath by nails 10a or other securing elements.

30 Fig. 6 illustrates the improvements embodied in a corrugated sheet metal roof having the corrugated sections 1b provided with the portions 2b and 4b adapted to overlap, the portions 2b having the upwardly curved 45 portions 3b to fit the curved portions 5b and abut the doubled portions 6b in the manner hereinbefore described, the portion 4b having the upstruck rib 8b on which the portion 2b seats, similar to the portions 2 and 8 above described. The portion 4b is secured on the board underneath by a nail 10b.

35 In each embodiment of the invention each roof element is provided along one edge with a slot leading to a cavity between the doubled resilient portion overhanging the slot and the upwardly curved portion, for receiving the upwardly curved edge portion of the companion roof element to provide a tight joint which is concealed from view and 40 which will give assurance against leakage.

Having thus described the invention, what is claimed as new is:

45 A sheet metal roof element to be assembled with other similar roof elements, having an edge portion, a doubled resilient por-

tion overhanging said portion, and an upwardly curved portion connecting the first named portion with said doubled portion, said element having an opposite upwardly curved edge portion to snugly fit the aforesaid upwardly curved portion of a companion roof element when said elements are wedged together and to abut the doubled portion of said companion roof element at the juncture of said doubled and upwardly curved portions, the first named portion of the roof element having an upstruck rib for the contact of a companion roof element when the upwardly curved edge portion of said companion roof element is positioned between the doubled and upwardly curved portions, the doubled portion being spaced from and so arranged with reference to the upwardly curved portion that the upwardly curved edge portion of the companion roof element is disposed between them from said doubled portion excepting at the edge which is in abutment with said doubled portion, and fastening elements for securing said metal roof elements in place, said fastening elements being disposed outwardly of said upstruck rib.

In testimony whereof I hereunto affix my signature.

ROSS A. WORKMAN.
